CLOSURE AND METHOD OF MANUFACTURING THE SAME

Charles E. McManus, Spring Lake, N. J., assignor
to Crown Cork & Seal Company, Inc., Baltimore, Md., a corporation of New York

Application March 23, 1934, Serial No. 717,104

2 Claims. (CL. 113—121)

The present invention relates to caps of the type including a cup-shaped shell and cushion liner. It is distinguished from a crown cap in the following respects: (1) The shell is provided with a plane circumferentially smooth skirt, i. e., devoid of vertical corrugations. (2) The skirt has at its lower end an integral rim extending at substantially right angles to the skirt. (3) The rim has the metal thereof doubled under and inwardly upon itself, flattened, and is corrugated to form locking shoulders adapted to engage beneath the sealing bead of a container when the cap is applied thereto.

By having the skirt smooth and unobstructed, not only is the cap rendered more attractive, but the sealing capacity is very materially enhanced. For example, there are no corrugations or fluted portions in the skirt which would be expandible, and the skirt therefore when drawn over the sealing lip and bead of the container will closely fit and follow the contour of the same. This is important because when the cap is applied to a container, the lower edge of the skirt is drawn beneath the sealing bead and continuously grips the bead circumferentially, exerting a very high downward sealing pressure. This downward sealing pressure is directly translated to the top of the cap and its cushion liner and therefore directly to the lip of the container with which the cushion engagess.

I find by using an integral rim extending at right angles to the smooth and unobstructed skirt, that the cap and rim will be drawn down without requiring that the skirt be engaged by the cap applying throat so that the skirt when the cap is on the container remains smooth at all times and is not indented by the sealing operation. In other words, the cap applying throat will only engage the rim to bend it downwardly and the skirt being plane, will not be engaged by the throat, whence no weakening or expandible indentations will be formed in the skirt.

By folding the metal of the rim, i. e., doubling it under and inwardly upon itself and flattening the doubled metal, the rim is strengthened and stiffened so that the cap holds its shape. This also enables the cap to be prized from a container without distortion. The usual crown when subjected to a prizing tool is so distorted as to not be capable of reuse. The present cap, however, is prized with a minimum of distortion and retains its resiliency and shape whereby it can be reapplied to the container to form an effective seal. The thickened and stiffened rim translates and distributes the prizing strain upon either

side of the point of engagement of the prizing tool with the cap so that the cap is removable with but a very slight lifting force. This it will be appreciated also aids in eliminating the possibilities of distortion and enables the cap to be used as a reseal.

As stated, the rim is provided circumferentially with corrugations or flutes. These corrugations are characterized by plane portions extending substantially parallel to the top of the cap and at right angles to the skirt. The plane portions are spaced apart by substantially V-shaped or U-shaped portions, the ridges of which are likewise parallel to the top of the cap and to the plane portions and extend radially at right angles to the skirt.

When the cap is applied to a container, the skirt and the rim are drawn downwardly; the rim is bent from a position at right angles to the skirt to a vertical position with the plane portions of the corrugations disposed beneath the sealing bead of the container to form locking shoulders and the substantially V-shaped portions forming in effect projections of the skirt; and the lower edge of the skirt is drawn beneath the sealing bead of the container to continuously grip the same circumferentially. As stated, the plane portions of the corrugations form inwardly extending locking shoulders lying in a vertical plane which is substantially a projection of the sealing bead of the container while the substantially V-shaped or U-shaped portions lie in a vertical plane which is a projection of the skirt. There is a slight flare produced by the substantially V-shaped or U-shaped portions such as will readily permit the entrance of a prizing tool between the cap and the neck of the container.

The downward sealing pressure exerted by the cap upon the cushion and sealing lip of the container is the sum of two forces. In the first place, the inwardly drawn lower edge of the skirt has a substantially continuous gripping engagement with the under-surface of the sealing bead of the container; and second, the inwardly directed locking shoulders formed by the plane surfaces of the corrugations enhance and rigidify this gripping engagement. Moreover, the bending of the rim downwardly and the drawing of the locking shoulders and the lower edge of the skirt beneath the bead produces a reaction in that the substantially V-shaped or U-shaped portions of the corrugations are collapsed or drawn together, thereby fortifying the circumferential gripping engagement between the lower edge of the skirt and the under-surface of the sealing bead.

- At the same time the cap is rendered resilient and flexible so that when removed, it may be easily reapplied and form an efficient seal. Stated briefly, the collapsing of the corrugations 5 produces in effect radial vertically disposed stiffening projections.
- The advantages of the present construction aside from the remarkable sealing and resealing qualities which it possesses, also include a very 10 important saving in manufacturing costs. For example, the cap of the present invention may be manufactured from much thinner gauge metal than the usual crown caps; a sealing liner of substantially one-half the thickness of the usual liner is employed; and a cheaper adhesive is utilized. These are important considerations when it is considered that more than eighty million gross of caps of the crown type are manufactured yearly.
- 20 Referring to the drawing: Figure 1 is a sectional view of a hat-shaped shell or blank; Figure 2 is a sectional view showing the marginal edge of the shell curled inwardly; Figure 3 is a bottom elevation of a shell of the structure shown in Figures 1 and 2 having the rim portion provided with corrugations; Figure 4 is a sectional view on the line 4-4 of Figure 3; Figure 5 is an enlarged sectional view partly broken away showing in detail the flattened and folded edge portion of the rim and the indentations formed therein; Figure 6 is an elevation showing the cap applied to a container such as a bottle for beverages or alcoholic liquors; Figure 7 is a sectional view of the cap applied to a bottle with the lower edge of the skirt and the plane portions of the corrugations drawn inwardly beneath the sealing bead of the container and with the substantially V-shaped or U-shaped portions of the corrugations collapsed or drawn together and forming in effect projections of the skirt.
- 45 The cap of the present invention is formed from relatively thin sheet metal and preferably of a gauge lighter than that used in the manufacture of the customary crown or crimped caps. In the operation of forming the cap, the metal 50 is first drawn into the form of a hat-shaped shell 10 having a top 11, a skirt 12 and an integral rim 13 extending parallel with the top of the cap or at substantially a right angle to the skirt 12 with which it is integrally connected at the lower edge 55 of the skirt, all as shown in Figure 1.
- The raw edge or marginal portion 14 of the rim 13 of the hat-shaped blank is curled inwardly beneath the rim as shown in Figure 2 to partially underlie the same. This curl may extend 60 completely under the rim, but preferably the under-folded portion partially underlies the rim, so that the curl is adjacent its outer periphery.
- The blank comprising the cup-shaped shell with smooth unobstructed skirt and rim having 65 the curled circumferential portion 15 is now subjected in a suitable machine to a corrugating of the rim portion and flattening of the curl as shown in Figures 4 and 5. In the corrugating operation, the curl is flattened against the under 70 side of the rim, as shown at 16 in Figures 4 and 5. The corrugations are in the form of plane portions 17 extending in a plane parallel to the top of the cap and at substantially right angles to the skirt. The plane portions of the corrugations are spaced apart by alternate intermediate
- portions 18, which are substantially V-shaped or U-shaped in cross-section with the ridges thereof lying in a plane parallel to the top of the cap and the plane portions 17, and extending radially at substantially right angles to the skirt. The 5 ridges and plane portions merge with the lower edge of the skirt or curved lines as shown in Figures 4 and 5 at 19.
- While I have described the folded or doubled portion of the rim 15, 16 as being flattened, it 10 will be understood that in some cases the portions of the folded metal lying within the V-shaped or U-shaped portions 18 of the corrugations alone are flattened, while the portions of the folded metal coextensive with the flattened portions 17 15 of the corrugations are not forced into contact with the adjacent under-surface of the rim, being relatively open.
- In curling the rim as described, any irregularities in the raw edge are removed and the edge 20 of the rim becomes uniform, while at the same time the raw edge is concealed, so that there is no danger of cutting the fingers or of having the edge of the cap rust.
- It is to be observed that the skirt 12 is circumferentially plane and unobstructed; in other words it is not vertically corrugated and the corrugations are disposed entirely in the circumferential rim 13. This rim is reinforced and stiffened by the in-folding of its margin or circumferential edge to lie beneath the undersurface of the rim and in contact therewith, i. e., wholly or partly flattened as described. These are important features of the invention in that a very high sealing pressure will be exerted upon the 35 cap, and in addition the cap resists deformation so that it may be reused as a seal without seriously affecting its sealing qualities.
- The cap is applied to a container by drawing the same over the sealing lip thereof. In Figure 40 7, I have shown, partially in section, the sealing lip of a container having the sealing bead 20. When the cap is applied to this container, the skirt and rim are drawn downwardly thereover. The rim is bent to a position as shown in Figures 6 45 and 7 with the plane portions 17 thereof extending beneath and within the projection of the sealing bead 20; the U-shaped or V-shaped portions 18 extend downwardly substantially in a line with or as a projection of the skirt 12. The U-shaped 50 or V-shaped portions may present a slight flare but, in general, they form continuations of the projection of the skirt.
- The capping throat, by which the caps are applied and which serves to draw the plane portions 55 17 inwardly beneath the sealing bead so that they form inwardly directed locking shoulders, also draws the lower edge 21 of the skirt inwardly beneath the sealing bead 20 as shown in Figure 7. This inward folding of the lower edge of the skirt 60 assures a continuous circumferential gripping engagement of the skirt with the adjacent undersurface of the bead 20 of the container and produces a very high downward sealing pressure. The effect of this high sealing pressure will be 65 appreciated since the skirt, being free and unobstructed, the sealing force created by the drawing of the skirt downwardly and inwardly to engage the sealing lip, is directly translated to the top and cushion of the cap and hence directly to 70 the sealing lip of the container.
- Referring to Figure 7, it will be noted that the cushion 22, which, because of the high sealing pressure obtained with the present cap, need be only half the thickness of the usual cushion liner, 75

is also compressed in a manner to afford an enhanced side sealing, as shown at 23.

This very high downward sealing pressure afforded by the cap of the present invention is made possible by the drawing downwardly of the skirt and rim upon the sealing lip of the container whereby the inwardly directed locking lugs produced by the plane portions 17 are drawn under the sealing bead 20, at the same time drawing the lower edge 21 of the skirt into gripping engagement with the undersurface of the sealing bead 20. This operation, moreover, causes the U-shaped or V-shaped portions 18 to be collapsed or have their sides moved inwardly substantially towards each other, due to the bending of the rim downwardly. This collapsing of the corrugations serves to rigidify the cap and particularly acts to intensify the engagement of the lower edge of the skirt with the under-surface of the sealing bead of the container. Hence, the downward sealing pressure is the sum of the gripping forces exerted by the lower edge of the skirt upon the sealing bead plus the tension exerted by the collapsing of the V-shaped or U-shaped portions of the corrugations. In effect, these collapsed corrugations form vertically disposed radially extending stiffening projections which resist any tendency of the gripping engagement of the lower edge of the cap with the sealing bead of the container to loosen. When the cap is prized from the container, however, these collapsed projections constitute resilient means enabling the cap to be pressed over the sealing lip and bead and acting to produce a downward sealing force sufficient to assure an effective resealing.

Referring to Figure 7, it will be observed that the inwardly directed locking shoulders 17 are sufficiently spaced from the wall of the container to permit the insertion of a suitable prizing tool. Since the prizing tool will engage the rim only of the cap, and since the rim is circumferentially reinforced, a very slight pressure is necessary to remove the cap over the sealing bead. That is, the rim being stiffened, in the exercise of the prizing action, the force is translated for a considerable distance on either side of the point of engagement of the prizing tool with the cap and in this manner, only a relatively slight force is necessary and particularly one which will not distort the cap and interfere with its resealing value.

Further, with respect to the application of the cap to the container, by reason of the rim of the present invention, the throat of the capping tool will only engage the rim so that the skirt when applied to the container will remain free and unobstructed, as shown in Figures 6 and 7. Briefly, since the skirt is not provided with indentations of any sort, it is possible to utilize a cylindrical throat to engage only the rim whereby the latter and the skirt are drawn downwardly in the manner above described and

there is no engagement or action upon the skirt, such as would indent or weaken it. As heretofore stated, the downward sealing pressure produced by the drawing of the rim and skirt downwardly and inwardly with respect to the sealing bead is translated directly to the top of the cap and the sealing lip.

By reason of the formation of the corrugations in the flattened, doubled or folded rim, they are substantially permanent. This structure, in combination with a smooth and unobstructed skirt, gives to the cap a flexibility and resilience which permits it to be easily removed without distortion and reapplied to the sealing lip to remake the seal. In the case of where the contents are to be used from time to time, this is an important feature, particularly since when the cap is reapplied to the sealing lip a highly efficient seal is produced, due to the resilience of the rim and the skirt.

I claim:

1. The method of manufacturing metal caps which comprises forming a hat-shaped blank having a top, a substantially smooth and unobstructed skirt, and an integral rim extending at right angles to said skirt, bending the peripheral edge of the rim beneath the rim to partially underlie the same and preserving the right angle direction of the rim, corrugating the rim including the doubled metal portion thereof and flattening the bent under portion against the rim and preserving the right angle direction of the rim during the corrugating operation and producing in the rim by the corrugating step, plane portions adapted to form locking shoulders engaging beneath the bead of a container and ridges adapted to form projections of the skirt when the cap is applied to a container and the rim is drawn downwardly.

2. A metal cap for containers comprising a hat-shaped shell having a top, a substantially smooth depending skirt and an integral rim extending at substantially right angles to the skirt, the peripheral edge portion of the rim being turned under the rim for a portion of the area thereof to form a doubled edge, said rim and doubled edge portion being corrugated and the turned under portion being flattened against the underside of the rim, said corrugations being defined by plane portions and ridges, the plane portions when the cap is applied to a container forming inwardly directed locking shoulders engaging beneath the bead of the container and the ridges forming projections at the skirt, said skirt having its lower edge portion engaging beneath the bead of the container, and said ridges being collapsed so that the engagement of the skirt portion with the bead of the container is substantially continuous with the collapsed ridges forming a multiplicity of spaced stiffening members depending therefrom.

CHARLES E. McMANUS.
